his Attorney

UNITED STATES PATENT OFFICE.

STERNE MORSE, OF YONKERS, NEW YORK.

MAKING PHOTOGRAPHIC FILMS.

Application filed August 22, 1921. Serial No. 494,357.

To all whom it may concern:

Be it known that I, STERNE MORSE, a citizen of the United States, residing at Yonkers, in the county of Westchester and **5** State of New York, have invented certain new and useful Improvements in Making Photographic Films, of which the following is a specification.

This invention relates to making photographic films; and it comprises a method wherein such films are made in an atmosphere of regulated moisture content and also of regulated content of carbon dioxid, of ammonia, or of both, such content being substantially greater than that normal to air; all as more fully hereinafter set forth and as claimed.

Photographic emulsions are colloid systems containing silver halide as a dispersoid in a state of extreme subdivision. With the halide are associated a film forming substance which is generally gelatin or pyroxylin and one or more of the many other materials commonly known as sensitizers, accelerators, ray selecting materials etc., not necessary here to be described in detail. It is well established that in the film the silver halide grains have a dissociation tension as regards the halogen, in most cases a very small one. To some extent the gelatin or collodion of the film, whether by means of adsorption on its internally developed surfaces or by chemical addition or both, takes up a certain small proportion of the evolved halogen until the rate of change of its content of halogen with respect to time, equals that of the silver halide grains. It therefore follows, since the internally developed surfaces of the gelatin or collodion remain largely constant whatever the amount of dispersion of the silver halide, that the amount of halogen contained in the silver halide, will be a function of its dispersion inasmuch as the above mentioned rates of change have the surface of the reacting bodies as a factor. It is probably due to this fact that the speed of photographic films is an inverse function of the size of grain. Another factor is the rate of absorption by a given area of surface. By influencing the state of acidity of the menstruum we can affect the rate at which it will absorb the halogen and consequently the composition and properties of the sensitive grain.

55 After the film is applied to the carrier and has set, it is of course necessary to dry it

and in this drying many expedients have been proposed and are now in use. The same phenomena hold good during this period of drying; rates of change however, changing as water is abstracted.

The present invention relates to a method of affecting the physical state of these emulsion films. In drying the films are exposed to the action of air in a suitable dark chamber. Better drying, that is drying with a better texture and surface, is effected where the air used in drying contains a certain amount of water vapor or is "conditioned". In drying first with air containing relatively large amounts of humidity and later with air of less humidity, better results are obtained than in using absolutely or relatively dry air ab initio. Similarly, when the emulsions contain volatile solvents, it is often desirable to dry at first in an atmosphere containing these bodies.

I have discovered that a further improvement in the character of the dried film may be effected by regulating not only these factors but also the H ion concentration in the film during drying; this being particularly true with regard to gelatin emulsions, although also true of pyroxylin emulsions. In either case, the H ion concentration of the film during drying greatly influences the character of the dried film. In the present invention I utilize this fact by conditioning the air with carbon dioxid, with ammonia, or with both, as well as with water or other volatile materials. The proportion of carbon dioxid which is desirable in the air varies with the stage of the process, the character of the emulsion and the exact type of surface required. But it is always advisable to have a controlled CO₂ concentration and usually of ammonia as well in the atmosphere during drying and during other operations in which extensive surfaces are exposed to such atmosphere. In any liquid or emulsion of this character, exposed to an atmosphere in which either CO₂ or NH₃ occurs, or in which both are present, the H-ion concentration will be influenced by the proportion of CO₂ or NH₃ in the atmosphere. Proportions of carbon dioxid running from amounts below that normal to the atmosphere (say 4 volumes in 10000) up to 50 or 60 per cent are useful in various relations.

Any material which is in a state of fine division whether in the form of actual fibers

or particles or in the form of a continuous microscopic or submicroscopic network and which is not by itself highly buffered as regards its hydrogen ion concentration, may 5 be more or less stabilized in its hydrogen ion concentration (at least as regards its surface) by contacting it with an atmosphere containing either carbon dioxide or ammonia and such stabilization can be made more 10 exact within a certain limited but highly useful range by contacting it with a mixture of both gases. Proteins (of which gelatin is one) particularly have an entirely different set of reactions, according as the hydrogen 15 ion concentration is either at or above or below the isoelectric point of the particular protein concerned. Pyroxylin is also sensitive in somewhat similar ways but according to different principles. The results are 20 like though the reasons are different.

In drying films with conditioned air, that is conditioned as regards moisture, the air is often used in a more or less cyclic manner, being passed over the film to take up moisture, relieved of the amount so taken up and once more sent to the drying chamber. Such a cyclic circulation of air is usually employed where the air is to be conditioned with volatile solvents, such as alcohol, acetone, etc., in addition to, or instead of, water vapor. This cyclic circulation system can well be used in the present invention it being merely necessary to include an inlet connected to a source of carbon dioxide produced in any suitable way and from any suitable material and place in the cycle means for regulating the proportion of carbon dioxide in the circulating gases. In so doing I utilize the principles laid down in 40 my prior and copending application, Serial No. 450,952, filed August 22, 1921.

Solutions of alkaline carbonates, sodium carbonate and potassium carbonate, as well as those of the rarer corresponding rubidium, cesium and lithium carbonates, tend to form bicarbonates or acid carbonates by absorption of CO₂. The extent to which this bicarbonate formation goes forward depends upon the concentration of carbon dioxide in 50 the atmosphere in contact with the carbonate solution; and with intimate contact equilibrium conditions result. At any particular temperature a solution containing a particular amount of CO₂, or ammonia, or both as 55 bicarbonate has a certain definite CO₂ or NH₃ tension as the case may be. This principle is utilized in the present invention; this utilization being in either of two ways. In one way, the passing air or gas receives 60 direct additions of CO₂, NH₃, or both, in about the desired proportions and exact adjustment is effected with the aid of a carbonate solution adapted to take up temporary excesses of CO₂ (or of ammonia or of 65 both) and give off CO₂ (or ammonia or

both) to balance deficiencies. The solution acts, so to speak, as a balancing and averaging means. In the other way, a carbonate solution is circulated through two chambers, being in contact with the air to be conditioned in one and with gases rich in CO₂, such as washed products of combustion, in the other. 70

The difficulty with the use of a carbonate solution in this manner is that it possesses a 75 definite water vapor tension as well as a definite CO₂ tension at any particular temperature; and the proportion between the two may or may not be what is wanted in the particular operation. This may be easily 80 obviated by making water conditioning follow CO₂ conditioning; or still more simply by using "buffer salts" in the carbonate solution and thereby adjusting the CO₂ tension. These buffer salts are alkali salts of weak 85 acids, such as lactic acid, acetic acid, citric acid, etc., which are capable of being displaced from their salts to a greater or less degree by CO₂. At any given temperature a 90 solution of any of these salts together with a given carbonate solution has a definite CO₂ tension which, however, is different from that of the bicarbonate solution alone. So by mixing a solution of one of these buffer salts with a solution of a bicarbonate, it is 95 possible to vary the CO₂ tension at particular temperatures. 95

For any solution which contains a large amount of non-volatile buffer salts such as mixture of alkaline phosphates and the like, the carbon dioxide tension of the solution is a linear function of the total amount of combined carbon dioxide, i. e., the proportion which the carbon dioxide tension, numerically expressed, bears to the combined carbon dioxide, numerically expressed, is constant. The true form of the curve is probably hyperbolic. 105

In the accompanying illustration, I have shown diagrammatically an assemblage of 110 apparatus elements such as may be used in the present invention. The showing is purely diagrammatic.

In the figure, A is a drying chamber or work chamber, as the case may be, or any casing or room in which extensive surfaces of emulsion are presented to the atmosphere, whether for the purpose of working with emulsions, as in spreading, or in drying, etc. From this chamber air to be used in adjusting the H-ion concentration of the film passes through conduit 1 by means of fan 2 to conditioning tower B. The conditioning apparatus may be any type of chamber or tower in which air or other gases may be exposed to extensive surfaces of liquids. Any of the ordinary types of "scrubbers," column stills, etc., may be employed. As shown, the conditioning element B is a vertical tower provided with internal sloping shelves 3. 120 125

The air or gas enters near the bottom and passes upward through the tower in counter-current to down-flowing liquid, emerging finally through conduit 4, which returns it 5 to the work chamber. Down-flowing liquid, which may be a solution of carbonates or any of the other liquids described, enters through distributor 5 and flows downward in countercurrent to upward passing gas, being 10 filmed out on the described shelves. At the bottom of the chamber, it passes to exit through outlet 6, shown as comprising a rose or the like 7 in liquid adjusting chamber C. This chamber C likewise may be of 15 any of the usual types of scrubbers, etc., adapted for producing intimate contact between gases and liquids. As shown, it is provided with shelves 8 like those in the conditioning tower. The liquid flows down- 20 ward through this liquid adjusting chamber and passes to exit at the bottom through pipe 9 communicating with rotary pump 10 and return pipe 11 which takes it back to the distributing device 5 in chamber B. 25 Passing upward through this adjusting chamber C is a current of gas from any suitable source, carrying the gas to be absorbed by the circulating liquid. In case only CO₂ is to be added to the liquid, this 30 gas may be products of combustion only. This gas enters the adjusting chamber C through inlet 12 near the base and passes to exit through outlet 13.

What I claim is:—

- 35 1. The process of making photographic emulsion films which comprises exposing such films during manufacture to an atmosphere containing regulated but substantial amounts of CO₂.
- 40 2. The process of making photographic emulsion films which comprises exposing such films during manufacture to an atmosphere containing regulated but substantial amounts of a gas capable of altering the 45 H ion concentration in the film surfaces.
- 45 3. In the making of photographic emulsions the process which comprises passing air in contact with a solution of carbonate and bicarbonate to impart definite amount 50 of CO₂ thereunto and carrying out the manufacture in the air so treated.
- 55 4. In the manufacture and drying of photographic emulsions the process which comprises charging air with definite proportions of CO₂, by passing such air in intimate

contact with a solution containing a carbonate and a bicarbonate and also containing a buffer salt and then passing the air so treated in contact with an emulsion to be dried. 60

5. In the manufacture and drying of photographic emulsions the process which comprises establishing and maintaining a circulating body of liquid containing bicarbonate in one period of its travel passing 65 said body into contact with gases rich in CO₂, and in another part of its travel passing it into contact with air to be enriched in CO₂ and preparing, spreading and drying an emulsion in the presence of the air so 70 enriched.

6. In the drying of photographic emulsions the process which comprises establishing and maintaining a circulating body of liquid containing bicarbonate and also containing a buffer salt into contact with gases rich in CO₂, and in another part of its travel 75 passing it into contact with air to be enriched in CO₂, and drying an emulsion with the air so enriched. 80

7. In the making of photographic emulsions the process which comprises the carrying out of the processes of precipitation of silver halides in the emulsion in an atmosphere containing adjusted amounts of a foreign gas, said foreign gas comprising ammonia. 85

8. In the making of photographic emulsions the process which comprises the carrying out of the processes of precipitation of 90 silver halide in the emulsion in an atmosphere containing adjusted amounts of a foreign gas, said foreign gas comprising ammonia and carbon dioxide.

9. In the process of making photographic 95 sensitive films, the securing of an adjusted hydrogen ion concentration in the film by preparing it in an atmosphere of adjusted content of carbon dioxide and ammonia.

10. In the manufacture of photographic 100 sensitive films, the process which comprises maintaining a given hydrogen ion concentration in such films by maintaining in the atmosphere to which such films are exposed a regulated proportion of a gas regulating 105 the hydrogen ion concentration of such films.

In testimony whereof, I have hereunto affixed my signature.

STERNE MORSE.
